UNITED STATES PATENT OFFICE

124,192

DESIGN FOR AN AGITATOR

Owsley E. Carman, Vale, Oreg.

Application September 11, 1940, Serial No. 94,960

Term of patent 14 years

To all whom it may concern:

Be it known that I, Owsley E. Carman, a citizen of the United States and a resident of Vale, in the county of Malheur and State of Oregon, have invented a new, original, and ornamental Design for an Agitator, of which the following is a specification, reference being had to the accompanying drawing, forming part thereof.

Figure 1 is a perspective view of an agitator showing my new design.

Figure 2 is a horizontal sectional view taken along the line 2-2 of Figure 1 looking in the direction of the arrows.

Figure 3 is a horizontal sectional view taken through Figure 1 along the line 3-3 and looking in the direction of the arrows.

The dominant features of the design reside in an agitator of the form illustrated, having blades of the configuration shown associated with the lower portions of the shaft.

I claim:

The ornamental design for an agitator, as shown and described.

OWSLEY E. CARMAN.
